United States Patent Office

Des. 201,725
Patented July 20, 1965

201,725

SUBMARINE

Franklin E. Rigsby and Woodrow Rigsby, both of 9524 Fritz Road, Fort Wayne, Ind.

Filed July 16, 1964, Ser. No. 80,900

Term of patent 14 years

(Cl. D71—1)

Fig. 1

Fig. 2

Fig. 3

FIG. 1 is a port side elevational view of a submarine showing our new design (the starboard side view being the same);

FIG. 2 is a top plan view thereof; and

FIG. 3 is an aft end elevational view thereof.

We claim:

The ornamental design for a submarine, as shown and described.
